FREIGHT CAR WITH DUMPING BODY

Henry C. Lima, Flushing, N. Y., assignor of one-fourth to Max W. Davis, Bridgeport, Conn.

Application May 30, 1944, Serial No. 538,014

2 Claims. (Cl. 105—273)

1

This invention relates to dumping cars, especially to railway freight cars with dumping bodies, and has for an object to provide an improved construction whereby the load may be easily and quickly dumped at either side of the car desired.

Another object is to provide a construction in which the car is divided into a plurality of sections any one of which may be dumped independently of the others and toward either side of the car.

Another object is to provide a car of this character in which the dumping of any desired section may be controlled from a control station on the car.

With the foregoing and other objects in view I have devised the construction illustrated in the accompanying drawings forming a part of this specification. It is, however, to be understood the invention is not limited to the specific construction and arrangement shown but may embody various changes and modifications within the scope of the invention.

In these drawings:

Fig. 1 is a side elevation of a railway freight car showing my invention applied thereto, parts being broken away to more clearly show the construction;

Fig. 2 is a top plan view of a portion of the operating mechanism for dumping the various sections, part of the frame or bed of the car being shown in section;

Fig. 3 is a transverse section substantially on the line 3—3 of Fig. 1;

Fig. 4 is a detailed horizontal sectional view of a portion of the hinge means for a dumping section, and

Fig. 5 is a vertical section substantially on the line 5—5 of Fig. 4.

The showing in the drawing is somewhat diagrammatical, specific details being omitted for the sake of clearness. The car comprises the usual trucks 10 with wheels 11 running on the rails 12 supporting the frame or bed 13, including a hollow construction 14 in which is mounted operating mechanism for dumping the various sections of the car. The material carrying portion of the car or body is formed in sections 15, four of these sections being shown in the drawing, each being a hollow body section extending the full width of the car and being about ten feet in length, although of course the dimensions may vary, depending on the size of the car and its construction. Each section, however, is mounted independently of each of the other sections and may be loaded and dumped independently of each

other. It may also be removed from the car independently of the other sections.

Each body section 15 is mounted on hinge means 16 located at opposite sides of the bed or frame so constructed and arranged that each body section may be tipped or dumped in either direction, or that is, toward either side of the car, as indicated in Fig. 3. A simple and effective means for mounting each section comprises a block 17 mounted on the top wall 18 of the bed or frame and secured thereon by any suitable means, such as bolts or rivets 19. Formed in the top wall of this block is a curved recess 20, preferably however, not running the full length of the block so that the outer end of the recess is closed by the transverse wall 21, but the recess opens through the other end wall so that a curved hinge member 22 may seat in the socket. This hinge member may conveniently be a circular tube running substantially the length of the section, there being a block 17 mounted at each of the four corners of the section and each tube 22 seating at its opposite ends in the sockets in a pair of these blocks. The transverse end walls 21 prevent the tubes sliding longitudinally in the sockets. It will be seen therefore that when the tubular hinge members are seated in the recesses in the four blocks the body section is effectively mounted and held in proper position on the bed or frame of the car, but that the tubular hinge members 22 may turn in the blocks 17 so that the body may be swung or tipped thereon in either direction or toward either side of the car, as indicated in Fig. 3, each hinge member or tube 22 being adapted to lift from its socket or block 17 to permit swinging of the body section about the hinge means at the opposite side of the car. Other types of hinge means may be employed, but that shown has been found to be very effective and of very simple and rugged construction.

Power means is provided for dumping or tipping each individual section as desired. The main part of this power means is mounted in the hollow base or frame portion 14 so that it is enclosed and protected and comprises a series of shafts driven by a suitable electric or other motor 23, or it could be operated by hand through a crank adapted to be applied to the end 24 of the shaft 25 and operated through a releasable clutch 26. The shaft 25 may be driven by the motor 23 through a releasable clutch 27 controlled by any suitable means such as a hand lever 28. The shaft 25 drives an intermediate longitudinal shaft 29 through suitable gearing and mounted on this shaft are a plurality of

gears 31 meshing with gears 32 and 33 on a series of short shafts 34 to 41 inclusive, each gear 32 and 33 being adapted to drive its respective shaft through a releasable clutch 42 controlled from a hand lever 43 through a connecting rod 44 or 45. On each shaft 34 to 41 is mounted a pair of drums 46 and 47 on which may be wound operating cables 48 and 49.

The control levers 43 for the individual body sections and also the control 28 for the motor 23 are preferably located at a control station 50 on the car, and this is preferably at the center of the car between the two inner body sections 15. Between each two adjacent sections 15 and also at each end of the car is an upright structural frame 51 and 52 respectively, and at the center of the car there are two of these frames 53 separated sufficiently to form the control station 50 and provide a space for the operator. The end frames 52 could be braced longitudinally by suitable bracing members 54. These frames may be of any suitable construction but as indicated in Fig. 3 they are shown as comprising upright channel or I-beam sections 55 at either side of the car with a similar top cross member 56 and an intermediate cross member 57. There also may be an upright central member 58 with suitable bracing as found desirable. Mounted in each frame at the upper part thereof and adjacent the end of the section 15 is a pair of grooved pulleys 59 over which run the cables 48 and 49 to similar grooved pulleys 60 and 61 mounted on each section 15 adjacent the opposite sides thereof at the lower part of the section and at its opposite ends whereby either side of the section may be lifted and the section tipped or dumped in either direction, as indicated by the full and dotted lines in Fig. 3, the free ends of the cables after passing over the pulleys 60 and 61 being secured to the adjacent frame 51, 52 or 53 as indicated at 62. The opposite side walls or outer walls of the individual sections 15 may be provided with gates or closures 63 hinged to swing at their upper ends by suitable pivotal supports 64. These gates or closures may normally be secured in closed position by a suitable catch or other securing means (not shown).

Operation is as follows:

When it is desired to dump any individual section 15 the securing catches or latches for the closures or gates 63 on the side on which it is desired to dump the material are released, then the operator at the control station by engaging the clutch 27 will start the shaft 29 operating, and then by engaging any one of the clutches 42 he may tip or dump any individual section 15 desired. Suppose for example he wishes to dump the left hand end section 15a to the left as viewed in Fig. 3. He will engage the clutch 42 on the short shaft 36. This will operate the drums 46 and 47 on this shaft to operate the cables 48 which operate over one of the pulleys 59 and the pulleys 61 at the opposite ends of section 15. This will raise the pulleys 61 to the position shown in Fig. 3, thus lifting the right hand side of the body section 15 to the position shown in full lines. This operation lifts the hinge means 22 at the right hand side of the body section from its supporting blocks 17 while the hinge means 22 on the left hand side of the body section turns in its supporting blocks 17 and acts as a pivot or hinge. The gate or closure 63 having been released, it may swing open as indicated to permit the material within the body section 15 to flow from the

section. By releasing the clutch 42 the weight of the section will carry it back to its original position which movement may be controlled by manipulating the clutch 42.

If it is desired to dump the section in the opposite direction or to the right hand side of the car the operator will engage the clutch 42 on the shaft 37 thus operating this shaft and the drums 46 and 47 thereon to operate the cable 49 running over the pulleys 60 to lift the left hand side of the section 15 to the dotted line position in Fig. 3. In this case the hinge means 22 at the left hand side of the section will be lifted from the hinge blocks 17 and the section will swing or turn on the hinge means 22 at the right hand side of the section, turning in its blocks 17. The same operation may be employed for any one or all of the sections 15. These sections may be either open at the top as where transporting coal or other material that it is not necessary to protect from the weather, or the tops may be closed and have suitable hatches or closures to use for transporting grain or other material which must be protected from the weather.

It will be clear from the above that each individual section may be readily dumped in either direction or toward either side of the car and that each section may be dumped independently of each of the other sections, although if preferred the shaft sections 36, 34, 38 and 40 could be connected so as to be operated together and similarly the shafts 37, 35, 39 and 41 could be connected so that all of the sections could be dumped together. It will also be seen that each individual section may be readily lifted and removed from the car by suitable crane or lifting apparatus after the operating cables 48 and 49 have been disconnected to either place the individual sections on a loading platform or on a truck without dumping the load and a different and empty or loaded section placed on the car in its place. Thus this car could be used to facilitate loading and unloading where it is not desired to dump the individual sections. The bearings on the hinge supports could be reversed, that is the tubular members 22 mounted on the supporting structure and the socket members 17 mounted on the container.

Having thus set forth the nature of my invention what I claim is:

1. A dumping car comprising a supporting structure, a plurality of containers mounted on said structure, means mounting each container to swing toward either side of the car from an upright intermediate position so as to dump the container at either side of the car, mechanism on the structure for swinging each individual container in either direction to dump the container comprising a longitudinal shaft, means for operating said shaft, secondary shafts operated at times by the first shaft, clutch means for controlling the operation of the secondary shafts by said longitudinal shaft, drums on said secondary shafts, and cables connected to the drums and to the opposite, laterally extending sides of the container and to the supporting structure to swing the container in opposite directions.

2. A dumping car comprising a supporting structure, a plurality of containers mounted on said structure, means mounting each container to swing toward either side of the car from an upright intermediate position so as to dump the container at either side of the car, mechanism on the structure for swinging each individual container in either direction to dump the con-

5
tainer comprising a longitudinal shaft, means for operating said shaft, secondary shafts parallel to the first shaft, manually controlled means for operating the secondary shafts from the first shaft, drums on the secondary shafts for operation by rotation of said shafts, and cables connecting the drums to the container and windable on the drums to swing the container in opposite directions by rotation of the drums.
